UNITED STATES PATENT OFFICE.

LOUIS M. MAHIAT, OF DETROIT, MICHIGAN.

SKIRT-SUPPORTER.

SPECIFICATION forming part of Letters Patent No. 416,477, dated December 3, 1889.

Application filed August 16, 1888. Serial No. 282,857. (No model.)

To all whom it may concern:

Be it known that I, LOUIS M. MAHIAT, a citizen of the United States, residing at Detroit, in the county of Wayne and State of Michigan, have invented certain new and useful Improvements in Skirt-Supporters, of which the following is a specification, reference being had therein to the accompanying drawings.

10 This invention relates to new and useful improvements in skirt-supporters; and the invention consists in the peculiar construction and arrangement of the parts, whereby the weight of the skirt is equally distributed 15 around the waist, or nearly so, of the wearer, while at the same time the symmetrical outline of the waist is not disturbed, but, on the contrary, made more shapely than without the use of my device, all as more fully herein- 20 after described.

In the drawings which accompany this specification, Figure 1 is a detached perspective view of my improved skirt-supporter. Fig. 2 is an elevation thereof. Fig. 3 is a 25 cross-section thereof with the supporting and supported garment indicated in dotted lines. Fig. 4 is a detached perspective view of one of the sliding hooks; and Fig. 5 is a perspective view showing the application of my device to 30 a dress.

A is a metal leaf-spring of suitable length to partly encircle the waist of the wearer, and is preferably provided with a sufficient normal spring to clasp the waist. It is also formed 35 with the back portion or the top edge thereof on a lower plane than the top edge of the ends or front portion, as shown in Fig. 2, to define a correct waist-line when worn around the waist. This leaf-spring is provided with 40 means for securing it to the inside of the waist-garment B at the waist-line, such means consisting, preferably, of a series of perforations a for attaching it by stitching within a pocket C, formed by a suitable fabric, or by means of 45 the belt usually secured to the waist-garment. D is a stationary hook secured to the cen-

ter of the spring, and E E are two similar hooks slidingly secured to the ends of the spring, preferably by securing them in adjusting-slots. These hooks project below the 50 lower edge of the spring, and may also be provided with means—such as suitable perforations b—for securing them to the dress-waist after they are placed in their adjusted position.

F are eyes adapted to engage with the hooks E, and these eyes are preferably provided with suitable means—such as the perforations c—to secure them in suitable relation with the hooks D and E near the upper 55 end of the skirt G.

In practice the manner of using the device will be well understood without further description.

The advantages of my construction are, 65 first, that a correct waist-line is given to the wearer, while the weight of the skirt is supported all around equally, and the rigidity of the whole device especially facilitates the hooking and unhooking; second, the natural 70 clasp of the spring prevents wrinkling of the garment, as the spring will always tend to draw the waist in position when displaced by the action of the wearer.

What I claim as my invention is— 75

In a skirt-supporter, the combination of the spring A, having the spring and curvature to form a correct waist-line, provided with the perforations a, the stationary hook D, the hooks E, having sliding engagement with the 80 spring and provided with the perforations b, and the eyes F, adapted to engage with the hooks, and provided with means for securing them to the skirt, all arranged to operate substantially as described.

In testimony whereof I affix my signature, in presence of two witnesses, this 31st day of July, 1888.

LOUIS M. MAHIAT.

Witnesses:

JOHN SCHUMAN,
J. PAUL MAYER.
